UNITED STATES PATENT OFFICE.

MOSES K. JOHNSON, OF UNADILLA, GEORGIA.

REPAIR SPOKE SOCKET.

Application filed August 1, 1922. Serial No. 579,010.

To all whom it may concern:

Be it known that I, MOSES K. JOHNSON, a citizen of the United States, residing at Unadilla, in the county of Dooly and State 5 of Georgia, have invented certain new and useful Improvements in a Repair Spoke Socket; and I do hereby declare the following to be a full, clear, and exact description of the invention, such as will enable others 10 skilled in the art to which it appertains to make and use the same.

This invention relates to an emergency or repair spoke socket.

In connection with vehicle wheels generally, it frequently happens that the spokes thereof break or sever from their tenon in the felly. My aim is to provide a novel, inexpensive, efficient, durable and improved 15 socket for use in such an emergency and 20 under such conditions, and one which does not require the services of a skilled mechanic for installation.

A particular object is to provide felly reinforcing plates and a means whereby a 25 portion of the hinged spokes may be appropriately removed to provide clearance for removing any part of the severed tenon which may project from the felly to facilitate attachment of my improved socket.

Another object is to provide an attaching 30 plate with a stud for disposition for extension of the spoke at the felly, and which has a shoulder to cooperate with the clamping means engageable with the stud and with 35 the hinged spoke.

Additional objects and advantages will 40 become apparent from the description following taken in connection with accompanying drawings illustrating one practical embodiment.

In said drawings:

Figure 1 is a fragmentary elevation of a wheel showing a spoke thereof repaired by means of my improvement;

Figure 2 is a vertical sectional view taken 45 through my improvement and the adjacent felly and spoke and substantially on line 2-2 of Figure 1, and

Figure 3 is a detail perspective view of the 50 stud employed and

Figure 4 is a detail perspective view of the clamping plate employed.

Like reference characters designate like 55 or corresponding parts in the different views.

A vehicle wheel is fragmentarily shown at A of which the felly is designated B and the spoke C. These spokes as usual are secured in suitable sockets in the felly as by means of the tenon D. In practice, spokes frequently break or sever from the tenon D 60 at the felly B, leaving said tenons in the felly and having no connection therewith. It is under such conditions that my invention is used.

In reducing the invention to practice, an attaching clip or plate 5 is provided, of any suitable length and material, so as to cover the inner peripheral surface of the felly B opposite the spoke repaired and covering 70 the tenon D. This plate 5 may be secured in place in any suitable manner as by means of bolts 6 passing through the felly B and attaching ears 7 of plate 5. In order that the portions of the tenon D which may 75 project beyond the inner peripheral wall of the felly B may be removed, and my invention accommodated, clearance is provided by cutting off the outer end of the spoke B at a distance from the felly B which provides a flat outer end on the spoke at 8.

Attention is called to the fact that the plate 5 of itself may be used to reinforce the felly B should it break or sever transversely.

In the case of repairing the spoke, a stud 9 is provided, being secured to the plate 5 in any suitable manner as by a fastening 10 and the inner end thereof directly abut and contact with the flat end 8 so that the 90 stud will in effect serve as an extension of the spoke. Said stud is enlarged toward the felly in order to provide a shoulder as at 11. In order to fasten the stud and spoke in rigid relation, any suitable means is employed for instance clamp plates 12 semi-cylindrical in shape, surrounding the stud and spoke and at their outer ends abutting said shoulder 11. A fastening bolt 13 may be provided to plates 12 and stud 9 while 100 another fastening bolt 14 may pass through the spoke C and plate 12.

In operation, when the spoke breaks, it is sawed off as explained at a distance from the felly to provide the flat end 8, after 105 which any projections from the tenon D may be removed. Plate 5 is then attached by the bolt 6. Stud 9 having been previously connected to the plate 5 alines with and abuts the spoke C. The clamp plates 12 are then 110

applied around the spoke and stud, abutting shoulder 11, after which the fastening bolts 13 and 14 are applied.

As merely one practical embodiment has 5 been illustrated and described, changes within the spirit and scope as defined by the appending claims may be resorted to.

What is claimed is:—

1. A fastening device to secure a spoke 10 to a felly, consisting of a plate attachable to the felly, a stud in continuation of the spoke extending from said plate intermediate the spoke and felly, and means to secure said stud and spoke in rigid relation.
- 15 2. A fastening device to secure a spoke to a felly consisting of a stud in continuation of the spoke intermediate the spoke and felly, means to secure the stud to the felly, said stud having a shoulder, and fastening

means embracing said stud and spoke in 20 abutment with said shoulder.

3. A fastening device to secure a spoke to a felly consisting of a plate attachable to the felly, a stud extending from the plate in continuation of the spoke intermediate the spoke and felly, said stud having a shoulder, clamping plates surrounding said spoke and stud with ends in abutment with said shoulder, and fastening means 25 passing through said plates, studs and 30 spoke.

In testimony whereof I affix my signature in presence of two witnesses.

MOSES K. JOHNSON.

Witnesses:

LEAH PERRY,
R. G. LUMSDEN.
